(57) **CLAIM**

The ornamental design for a chair component, as shown and described.

DESCRIPTION

FIG. 1 is a perspective view of chair component embodying the present invention;

FIG. 2 is a front view of FIG. 1;

FIG. 3 is a right side view of FIG. 1, the left side being a mirror image of the right side;

FIG. 4 is a top view of FIG. 1; and,

FIG. 5 is a rear view of FIG. 1.

The dashed lines in FIGS. 1-5 show the environment, but are not intended to and do not form a part of the claimed invention.

1 Claim, 2 Drawing Sheets
